NEBULIZER UNIT OR SIMILAR ARTICLE

John M. Blank, Charles E. Cox, George Zimmerman,
Wayne J. Zitkus, and James J. Nelson, Toledo, Ohio,
assignors to Owens-Illinois, Inc., Toledo, Ohio

Filed May 7, 1973, Ser. No. 357,900

Term of patent 14 years

Int. Cl. D24—01

U.S. Cl. D83—1 N

FIG. 1

FIG. 2

FIG. 3

FIG. 5

FIG. 4

FIG. 1 is a front elevational view of a nebulizer unit or similar article showing our new design.

FIG. 2 is an elevational perspective view depicting the front and one side thereof.

FIG. 3 is an elevational perspective view depicting the front and a side opposite from the side depicted in FIG. 2.

FIG. 4 is an elevational perspective view depicting the back and the side shown in FIG. 2.

FIG. 5 is an elevational perspective view depicting the back and the side shown in FIG. 3.

We claim:

The ornamental design for a nebulizer unit or similar article, as shown.
